UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,446, dated July 10, 1888.

Application filed March 17, 1888. Serial No. 267,569. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

In the accompanying photographs, Figure 1 represents my design in a single row of figures. Figs. 2 and 3 represent said design respectively in two rows and in six rows.

Similar letters of reference indicate like parts.

My design consists in the quadrangular elevation A. On the face of said elevation appears a pyramid having four outwardly-curved or convex faces, B C D F. Near the edge of the elevation A the surface thereof appears

slightly flattened, as at G, and the faces of the pyramid gradually curve to meet said flattened portion—that is, the pyramid-faces and said flattened portion do not appear to meet at a sharply-defined angle. The sides of the elevation A are straight and perpendicular to the surface from which said elevation projects. The elevations A appear, as at A' A'', &c., to produce a row with intervening channels B between said elevations.

I claim—

The design for surface ornamentation of walls, &c., substantially as herein shown and described.

FREDERICK KOSKUL.
